UNITED STATES PATENT OFFICE.

LEWIS K. WARNER, OF LEXINGTON, NEBRASKA.

TANK.

1,191,629.

Specification of Letters Patent. Patented July 18, 1916.

Application filed May 26, 1915. Serial No. 30,643.

To all whom it may concern:

Be it known that I, LEWIS K. WARNER, a citizen of the United States, residing at Lexington, in the county of Dawson and State 5 of Nebraska, have invented a new and useful Tank, of which the following is a specification.

This invention relates to metal tanks and one of its objects is to provide a sheet metal 10 tank made up of sections which can be nested together so as thus to reduce the cost of transportation, and which are so constructed as to be easily assembled, the joints produced being leak proof and being of such 15 strength that live stock standing in the tank will not injure the joints and cause leakage therealong.

A further object is to provide tank sections so constructed that they will not be 20 injured at the angles thereof while being transported, as is often the case where the parts are soldered together prior to shipment, the rough handling causing the joints to break open along the soldered portions.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

35 In the accompanying drawings the preferred form of the invention has been shown.

In said drawings:—Figure 1 is a perspective view of a portion of a tank embodying 40 the present improvements. Fig. 2 is a plan view of the tank. Fig. 3 is an enlarged section on line A—B Fig. 2.

Referring to the figures by character of reference 1 and 2 designate opposed sections 45 of a sheet metal tank. The bottom of section 1 is folded along the free edge thereof to form a flange 2' of double thickness, this flange merging into an upstanding inverted channel portion 3 terminating in a base 50 flange 4 which is fastened upon the bottom of section 1 in any preferred manner, as by means of rivets 5, solder, or both. The space within the inverted channel portion 3 is filled by a flat metal bar 6 which is placed 55 in position at the time of bending the metal. The upstanding edges of the wall of section

1 are similarly formed and angular plates 7 constituting bracing means are secured within the angles formed by the bottom and wall of the section 1 and against the sides of the channel members 3 upon said bottom and wall. 60

The section 2 of the tank has its free edge portion offset upwardly to form a longitudinal recess 8 thereunder, this upwardly offset portion being overhung by an inverted channel portion 9 integral therewith, there being a flange 10 along the inner side of the channel portion and which is secured to the bottom of section 2 by rivets, solder, or both. 65 70 The space within the channel portion 9 is filled by a flat bar 11 of suitable metal.

The upstanding edges of the wall of section 2 are constructed in the same manner as the described portion of the bottom of 75 said section and bracing plates 12 are secured to the angle portions, as in section 1.

Openings 13 are formed transversely within the upstanding channel portions 3 and 9 and the bars therein, the openings in 80 the upstanding portions of section 1 being adapted to register with the openings in the corresponding portions of section 2. When the tank sections are to be shipped they are preferably nested one within the other or 85 else shipped separately, and it is obvious that the same can be more readily handled and will occupy less space than where a complete tank is shipped. Furthermore there are no joints liable to break open during transportation and thus render the tank 90 unfit for use when set up.

In setting up the tank the flange 2' is inserted under the offset portion of the bottom of section 2 and a strip 14 of suitable packing material is interposed between the upstanding portions 3 and 9. Bolts 15 are then inserted through the registering openings 13 and, when tightened, will clamp the parts securely together, thus forming a 95 leak-proof joint. Importance is attached to the fact that the inwardly extending parts of the joints are reinforced by the inserted bars 6 and 11. This prevents injury to the joint should live stock stand within the 100 tank. 105

The braces 7 and 12 prevent lateral distortion of the sections while in transit and also constitute efficient reinforcements for the tank while in use.

110 Obviously by constructing a tank as herein described, it becomes possible to ship

tanks that would otherwise be too large to pass through the door of a car.

A further advantage resulting from the structure herein set forth is that should the 5 solder which holds the flanges 4 and 10 in position, crack or break, it would not result in the tank leaking, as the water would merely flow into the inverted channels 3 and 9.

10 Although the bottom of the section 2 has been shown offset in Fig. 3, this is not necessary under ordinary conditions where the tank is formed of very thin sheet metal.

What is claimed is:—

- 15 1. A sheet metal tank comprising opposed sections, inwardly extending channel portions along the free edges of the sections, reinforcing bars seated within the said channel portions, means for fastening the channel portions of the two sections together, and a longitudinal flange outstanding from the channel portions of one section and adapted to be lapped by the opposed section.
- 20 2. A sheet metal tank comprising opposed sections, the free edge portion of one section being folded to form an outstanding longitudinal flange, an inwardly extending inverted channel portion, and an attaching

flange, the free edge portion of the other section being bent to form an offset portion, 30 an inwardly extending channel portion, and an attaching flange, and reinforcing bars filling the channel portions on the two sections.

3. A sheet metal tank comprising opposed 35 sections, the free edge portion of one section being folded to form an outstanding longitudinal flange, an inwardly extending inverted channel portion, and an attaching flange, the free edge portion of the other 40 section being bent to form an offset portion, an inwardly extending channel portion, and an attaching flange, reinforcing bars filling the channel portions on the two sections, a packing material interposed between the channel portions of the two sections, and means extending transversely 45 through said channel portions and bars for binding them upon the packing material.

In testimony that I claim the foregoing 50 as my own, I have hereto affixed my signature in the presence of two witnesses.

LEWIS K. WARNER.
